CLAIM

The ornamental design for a display housing for a remote visual inspection device, as shown and described.

DESCRIPTION

FIG. 1 is a perspective view of a display housing for a remote visual inspection device. The items shown in phantom lines are for illustrative purposes only and form no part of the subject invention;

FIG. 2 is a plan view of the display housing for a remote visual inspection device of FIG. 1. The items shown in phantom lines are for illustrative purposes only and form no part of the subject invention;

FIG. 3 is a side view of the display housing for a remote visual inspection device of FIG. 1, the opposite side being a substantial mirror image of the side shown in FIG. 3. The items shown in phantom lines are for illustrative purposes only and form no part of the subject invention;

FIG. 4 is a back view of the display housing for a remote visual inspection device of FIG. 1. The items shown in phantom lines are for illustrative purposes only and form no part of the subject invention; and,

FIG. 5 is a front view of the display housing for a remote visual inspection device of FIG. 1. The items shown in phantom lines are for illustrative purposes only and form no part of the subject invention.
